August S. Greth, Santa Cruz, Calif.

Application August 3, 1940, Serial No. 94,201

Term of patent 14 years

To all whom it may concern:

Be it known that I, August S. Greth, a citizen of the United States, residing at Santa Cruz, in the county of Santa Cruz and State of California, have invented a new, original, and ornamental Design for a Combined Portable Bath and Shower Cabinet, of which the following is a specification, reference being had to the accompanying drawing, forming part thereof.

Fig. 1 is a front elevation;

Fig. 2 is a side elevation;

Fig. 3 is a top plan view; and

Fig. 4 is a transverse section; of a combined portable bath and shower cabinet, showing my new design.

I claim:

The ornamental design for a combined portable bath and shower cabinet, as shown.

AUGUST S. GRETH.
